UNITED STATES PATENT OFFICE.

JOSEPH BLUMENFELD, OF LONDON, ENGLAND, ASSIGNOR, BY MESNE ASSIGNMENTS,
TO COMMERCIAL PIGMENTS CORPORATION, A CORPORATION OF DELAWARE.

PREPARATION OF TITANIUM HYDROXIDE.

• No Drawing. Original No. 1,504,672, dated August 12, 1924, Serial No. 690,658, filed February 4, 1924.
Application for reissue filed August 9, 1926. Serial No. 128,322.

DIVISION A.

The invention relates to the hydrolytic treatment of solutions of titanium oxide in sulphuric acid with the object of preparing the hydroxide of titanium.

5 Such solutions are obtained by treating titaniferous products or minerals, such as ilmenite, with sulphuric acid.

The chemical composition of these solutions may vary within fairly wide limits.

10 The two most important variables are the concentrations of TiO_2 and H_2SO_4 . Solutions containing from 100 to 400 grms. TiO_2 per litre are of the usual strengths which have to be treated. For a molecule of TiO_2 15 the solution should contain 1-2½ or even more molecules of H_2SO_4 .

It has now been found that the yield of titanium hydroxide obtained by hydrolytic precipitation of such solution (heated at 20 about 100° C. during a certain time) as well as its properties, such as the rate of decantation, filtrability, state of subdivision of grain, colour after calcination, etc., depend not only on the final state of the system subjected to hydrolytic treatment but they depend also upon certain transformations which the constituents of the solution undergo before and during the precipitation of the titanium hydroxide and also upon 25 the way in which this final state of reaction is brought about. In effect, the solution of TiO_2 in H_2SO_4 , brought to a desired concentration either by dilution or by concentration, is heated to the boiling point in order 30 to produce the hydrolysis and becomes opaque after a comparatively long time, but if the content in H_2SO_4 , combined with TiO_2 , neglecting other bases, is equal to or exceeds 35 100 grms. per litre, a very poor yield in 40 titanium hydroxide is obtained. Moreover, the precipitate thus obtained, even if filterable, is only filtered with great difficulty.

The object of the present invention, therefore, is to obtain a satisfactory precipitate 45 (from the point of view of yield, filtrability and other properties) in a short time from solutions of the type mentioned above even in high concentrations.

The invention consists in preparing titanium oxide or hydroxide by hydrolytic pre-

cipitation by diffusion of titanium from one solution into another under the action of differential concentration and preferably also temperature.

The invention further consists in preparing titanium oxide or hydroxide by hydrolytic precipitation by diffusion of titanium from one solution into another accelerated by mixing.

The invention also consists in applying 60 the above processes in the presence of other substances so that intimately mixed precipitates are obtained.

Generally, the methods employed are as follows:—

(1) The solution obtained by reacting on the titanium material with sulphuric acid, heated to a temperature exceeding 60° C., is covered with a layer of cold water or hot water, either pure or containing such substances as may favour the process such, for example, as H_2SO_4 , H_3PO_4 , $Al_2(SO_4)_3$, SO_2 , or even a solution of titanium salt of a different concentration. The quantity of the liquid added is calculated so as to produce 70 on diffusion or mixing together the desired concentration. The liquid is introduced in such a manner that the two liquids may mix together only gradually, and thus within a certain time there will be a difference in 75 concentrations in different parts of the solution as regards H_2SO_4 and TiO_2 .

(2) In another or modified method the solution is concentrated by evaporating or boiling and may even become thick like a 80 paste. When the necessary quantity of water has been eliminated according to the object, the solution is mixed with a smaller, equal or larger quantity of water than that eliminated. One of the liquids must be at that time at a 85 temperature above 60° C.—usually the concentrated solution. The water may be pure or containing some substances, such as titanium salt or the like. The proportions of the two liquids are selected so as to have the desired concentration, both in TiO_2 and H_2SO_4 , in the final state after the complete mixing. The mixing should be effected fairly quickly 90 in order that the titanium hydroxide does not precipitate appreciably before the homo- 95 100

geneity of the solution is achieved and heating continued.

In both cases the hydrolytic precipitation is terminated at a temperature not far from the boiling point of the solution and in a constant volume. The yield of the precipitate reaches 85-95 per cent in a few hours in the first case and in less than one hour in the second. The various properties mentioned above are greatly improved, such as the filtrability as well as the stability of the mother liquor at dilution.

These methods are equally valid when the titanium hydroxide is precipitated in presence of other substances adapted to serve as constituents of paint pigments, (such as BaSO_4 , CASO_4 , SiO_2 and the like) with which it is desired to mix it very intimately. The added substances may be prepared separately or in the same apparatus in which the hydrolysis takes place.

Example 1.

The solution containing:—

	Gr. per litre.
TiO_2 —	225
Fe—	50
H_2SO_4 total—	440

is heated to 95-98° and a layer of cold water is placed on the top in quantity corresponding to about 20 per cent of its volume. This amount of water is sufficient to reduce the total H_2SO_4 content to about 367 grams per litre. The mixture of the liquids is facilitated by a gentle agitation. The liquid becomes gradually turbid and then a precipitate falls down. By the end of a few hours the yield of titanium hydroxide is about 94 per cent.

Example 2.

The solution containing:—

	Gr. per litre.
TiO_2 —	180
Fe—	42
H_2SO_4 —	460

is concentrated by evaporation to half its volume. It then has the consistency of a paste. It is introduced into about twice its own volume of boiling hot water so that the concentration finally will be 300-310 gr. H_2SO_4 per litre. The mixing is effected in such a manner as to avoid the immediate coagulation (precipitation) by delaying the mixing from 3 to 5 minutes. It is maintained at boiling temperature, evaporation being prevented. In about half an hour a yield of 85-95 per cent of titanium hydroxide is obtained.

In both of the illustrative methods of procedure mentioned above, it is stated that the water which is mixed with the solution of titanium salts may contain other substances such, for example, as the sulfuric acid or titanium salts. In certain of the claims I

have used the term "solution of lesser concentration" broadly as covering the diluent which is used in the process.

Having now described my invention what I claim as new and desire to secure by Letters Patent is:—

1. The preparation of titanium oxide or hydroxide by hydrolytic precipitation which comprises diffusing titanium from one solution into another under the action of differential concentration and temperature and allowing the diffusion action to continue for several minutes before mixing the solutions. 75

2. The preparation of titanium oxide or hydroxide which comprises the hydrolytic precipitation by diffusion of titanium from one solution into another, accelerated by mixing the two solutions after allowing the diffusion to continue for about 3 to 5 minutes. 80

3. The preparation of titanium oxide or hydroxide by hydrolytic precipitation which comprises diffusing titanium from one solution into another under the action of differential concentration and allowing the diffusion action to continue for several minutes 85 before mixing the solutions. 90

4. The preparation of titanium oxide or hydroxide by hydrolytic precipitation which comprises diffusing titanium from one solution into another under the action of differential concentration, and allowing the diffusion action to continue for several minutes before mixing the solutions, the proportions being such as to give, upon mixing, a content of total H_2SO_4 equal to about 300 to 310 grams 100 per litre of solution. 95

5. A process for the preparation of titanium dioxide or hydroxide by hydrolytic precipitation, which comprises bringing together a solution of titanium sulfate with a solution of lesser concentration and retarding the rate of admixture so that the titanium sulfate solution is gradually diluted. 105

6. A process for the preparation of titanium dioxide or hydroxide by hydrolytic precipitation, which comprises bringing together a solution of titanium sulfate with a diluent and retarding the rate of admixture so that the titanium sulfate solution is gradually diluted. 110

7. A process for the preparation of titanium dioxide or hydroxide by combining a solution of titanium sulfate with a solution of lesser concentration at an elevated temperature, which comprises gradually mixing said solutions. 115

8. In a process for the preparation of titanium dioxide or hydroxide by combining a solution of titanium sulfate with a diluent at an elevated temperature, the step which comprises gradually mixing the solution with said diluent. 120

9. A process for the preparation of titanium dioxide or hydroxide by hydrolytic precipitation, which comprises bringing to 125

gether a solution of titanium sulfate with a solution of lesser concentration and delaying the admixture of the solutions.

10. A process for the preparation of titanium dioxide or hydroxide by hydrolytic precipitation, which comprises bringing together a solution of titanium sulfate with a diluent and delaying the admixture of the titanium sulfate and the diluent.
11. A process for the preparation of titanium dioxide or hydroxide by combining a solution of titanium sulfate with a solution of lesser concentration at an elevated temperature and permitting diffusion to take place between the two solutions.
12. In a process for the preparation of titanium dioxide or hydroxide by combining a solution of titanium sulfate with a diluent at an elevated temperature, the step which comprises diffusing the solution with the diluent.
